UNITED STATES PATENT OFFICE.

CHESTER E. YOUNG, OF LAWRENCEVILLE, ILLINOIS.

OIL THIEF.

Application filed September 5, 1924. Serial No. 736,101.

To all whom it may concern:

Be it known that I, CHESTER E. YOUNG, a citizen of the United States, residing at Lawrenceville, in the county of Lawrence and State of Illinois, have invented certain new and useful Improvements in Oil Thiefs, of which the following is a specification.

This invention relates to sampling devices commonly known as thieves or oil thieves.

10 Devices of this character are used principally for detecting water in refined oils and crude oils, and are especially designed for use in detecting water in gasoline. The device is suspended by a cord and lowered 15 into a barrel or other receptacle containing the oil or gasoline to be sampled, until the lower end thereof rests upon the lowermost portion of the receptacle, whereupon the device will open to allow the fluid contained 20 in the bottom of the receptacle to flow thereto and when the device is raised from the bottom of the receptacle, it will automatically close and trap the fluid therein. If there is a layer of water upon the bottom of the 25 receptacle beneath the oil, the device will remove therefrom a certain amount of this water as well as a certain amount of the oil in the receptacle and the height of the water in the device will indicate the depth of 30 the strata of water in the bottom of the receptacle.

The primary object of this invention is the provision, in a manner as hereinafter set forth, of an oil thief for the purpose as 35 above set forth which will quickly and easily entrap a portion of the fluid to be examined and automatically closed as soon as raised from the receptacle to give accurate results as to the quantity of impurities in the oil 40 sample.

A still further object of the invention is the provision in a manner as hereinafter set forth, of an oil trap so designed that, when the trap is removed from the body of oil 45 in which it has been inserted, it will show at a glance the depth of water, if any, which might be lying at the bottom of the receptacle beneath the sampled oil.

A final object of this invention is the provision, in a manner as hereinafter set forth, of an oil thief of simple design, neat and attractive in appearance, giving accurate results, strong, durable, and inexpensive to manufacture.

55 The invention will be best understood

from a consideration of the following detail description taken in connection with the accompanying drawings forming a part of this specification, with the understanding that the invention is not confined to any strict conformity with the showing of the drawings but may be changed and modified so long as such changes and modifications mark no material departure from the salient features of the invention as expressed in the appended claims.

In the drawings:

Figure 1 is a side elevation of the device embodying this invention.

Figure 2 is a central longitudinal section- 79 al view of the same.

Figure 3 is a plan view of a valve seat for the upper portion of the implement.

Figure 4 is a plan view of a retaining nut by means of which a lining is retained in the 75 body of the device, and

Figure 5 is a transverse section upon the line 5—5 of Figure 2.

Referring now to the drawings in detail wherein like numerals of reference indicate 80 corresponding parts throughout the several views, the device embodying this invention comprises a substantially elongated cylindrical body 1 open at its upper end and interiorly threaded as at 2 and having its lower end formed to provide the annular in-turned flange 3 providing a reduced central aperture 4. A longitudinally extending opening is cut in the wall of the cylinder as indicated at 5, the lower portion of this 90 opening being adjacent the lower end of the cylinder and the top thereof being positioned a substantial distance below the upper end of the cylinder as shown.

The inner surface of the annular in-turned flange 3 is finished off to provide the shoulder 6 which supports a glass barrel 7, the overall diameter of which is substantially the same as the interior diameter of the cylinder to set up a snug fit between the two 100 bodies. A washer 8 is interposed between the shoulder 6 and the lower end of the cylinder 7.

A cylinder retaining nut 9 is provided having peripheral threads 10 thereon to engage the threads 2 in the upper end of the cylinder 1 and this circular nut is threaded into the cylinder 1 to bear against the washer 11 carried upon the upper end of the cylinder 7 to firmly clamp the same in position. 110

The nut 9 is provided with the axial bore 12 and further has the diametrically opposite radial slots 13 therein for the engagement of a tool to loosen the same or thread the same into position.

Closing the upper end of the cylinder 1 is a head member indicated as a whole by the numeral 14. This head member comprises a hollow dome 15 surmounted by the neck 16 and finger-hold or knob 17. An aperture 18 is formed through this knob 17 for the passage of a suspension element. Surrounding the lower portion of the dome 15 of the body is an annular knurled collar 19 from which there depends the skirt 20 provided with interior and exterior screw threads. This skirt 20 is of less thickness than the collar 19 and there is thus provided at the lower edge of the collar a shoulder 21. The skirt 20 is threaded into the upper end of the cylinder 1, as shown, until the top edge of the cylinder abuts the shoulder 21. The dome 15 is provided with a series of apertures 22, the purpose of which will become apparent as the description of the device proceeds.

Threaded into the skirt 20 of the head 14, is a top valve seat element constituting a substantially elongated annular body member 23 having the axial passage 24 therethrough and exteriorly threaded as indicated to threadably engage the interior threads of the skirt 20. One end of this member 23 is of greater diameter than the body and provides the head 25, the inner face of which head abuts against the end of the sleeve 20 as shown in Figure 2. A pair of diametrically opposite radial slots 26 is formed in the outer face of the head 25 to provide means for engaging the valve seat member with a tool to screw the same into or out of position. It will be noted that the passage 24 is of the same diameter and aligns with the passage 12 of the nut 9 and the lower face of the head 25 of the member 23 bears upon the top of the nut 9 when the head is in position. The member 23, as shown, closes the lower end of the hollow head 14 and there is thus set up a domed chamber 27 in the head which constitutes a ball valve chamber.

Positioned within the glass barrel 7 of the device is a vertically reciprocable rod 28 having the flat squared lower end 29 which constitutes a foot and which further has its under central surface recessed as at 30 to seat the foot upon a ball 31 which is normally seated upon the edge of the annular flange 3, and extends partially through the aperture formed thereby, as shown in the drawings. This ball seats perfectly in this aperture and normally tends to close the same. The upper end of the rod 28 extends through the passage 12 and into the passage 24 of the member 23, but does not

extend entirely through this passage, but terminates a slight distance below the end thereof. Carried upon the rod 28 a slight distance below the upper end of the barrel 7, is a second square disk member 32, the four corners of which, like the disk member 29, engage the inner wall of the barrel 7 and act to guide the rod in its longitudinal movement in the barrel.

Entrapped in the chamber 27, by means of the member 23, is a ball 33, which seats in the upper end of the passage 24, and which, when seated, is free from contact with the upper end of the rod 28, to allow it to seat perfectly in the end of the passage, to close the same. This ball besides acting to close the upper end of the barrel 7 against the entrance of fluid when the device is raised from the bottom of the receptacle, also acts to force the rod 28 downwardly to cause the ball 31 at the lower end thereof to quickly and positively seat in the aperture 4 to close the lower end of the barrel.

The glass barrel 7 is provided at spaced intervals of one inch throughout its length with the transversed marking indicated at 34, by means of which marking the depth of the strata of water in the bottom of the container of oil can be determined.

In the use of this instrument, a suspension means is passed through the aperture 18 in the knob 17, and the instrument is lowered into a barrel or other receptacle containing the oil or gasoline to be tested. The instrument is lowered until the ball 31 contacts with the lowermost portion of the receptacle, whereupon the ball 31 will be unseated, will lift the rod 28 which in turn will unseat the ball 33 allowing the liquid to enter through the aperture 4 into the barrel 7 and through the apertures 22, through the passage 24 and into the barrel 7. If the container in which the oil being tested is stored, contains at its bottom a stratum of water two inches in depth, this two inch depth of water will rise to the second marking from the bottom of the instrument as indicated by the numeral 34, and will stop at this point, oil entering through the aperture 22 to fill the rest of the barrel with oil. The condition within the instrument will then be the same as the condition of the oil within the receptacle and when the instrument is raised vertically from the bottom of the receptacle to remove it therefrom, the ball 31 will seat itself to close the aperture 4 and the ball 33 will immediately seat itself to close the passage 24 and what might be termed a transverse section through the oil and water of the container is removed therefrom, and a glance through the sight opening 5 into the glass barrel 7 will immediately indicate the depth of the water within the container to establish the purity and cleanliness of the oil contained therein.

Having thus described my invention what I claim is:

1. In a device of the character set forth, a relatively long tubular body having an aperture through the lower end thereof, a removable hollow head threaded into the upper end thereof, an axially bored removable closure threaded into the lower portion of said head, a longitudinally extending freely reciprocable rod within said body having the upper end extended partially through said bored closure, and a free ball member at each end of said rod, one supporting said rod and normally acting to close said lower aperture and the other within said head and normally acting to close the upper end of the bore of said closure.

2. A device of the character set forth, comprising a relatively long tubular body having an aperture through the lower end thereof, a removable hollow head threaded into the upper end thereof, an axially bored removable closure threaded into the lower portion of said head, a longitudinally extending freely reciprocable rod within said body having the upper end extended partially through said bored closure, a guide foot upon the lower end of said rod and bearing against the inner wall of said body, and a free ball member at each end of said rod, one recessed in said foot and supporting the rod and normally acting to close said lower aperture and the other within said head and normally acting to close the upper end of said bored closure.

3. A device of the character described, comprising a tubular body having the upper end open and having the lower end provided with a relatively small aperture, an apertured hollow head having an interiorly and exteriorly threaded lower portion threaded into said upper end, an axially bored closure member engaging said interior threads of the lower portion of said head, a freely reciprocable rod in said body having one end extended into the bore of said member, and a free ball member at each end of

said rod, one acting to normally close said small aperture and the other acting to normally close the upper end of said bore. 50

4. A device of the character set forth, comprising a tubular body having the upper end open and the lower end inwardly flanged to provide a relatively small lower aperture, said body being interiorly threaded at the upper end, a removable lining barrel snugly fitted into said body, means threaded into said upper end to retain said barrel therein, a hollow head removably threaded into said upper end, a removable 60 axially bored closure for the lower part of said head, a freely reciprocable rod in said body having one end extended into the bore of said closure, and a freely moving ball at each end of said rod, one supporting said 65 rod and normally acting to close said lower aperture and the other confined within said head and normally acting to close the upper end of said axial bore.

5. A device of the character set forth, 70 comprising a tubular body having the upper end open and the lower end inwardly flanged to provide a relatively small lower aperture, said body being interiorly threaded at the upper end and further having a relatively 75 long longitudinally extending sight opening formed therethrough, a removable glass barrel snugly fitted in said body and covering said sight opening, a retaining member threaded into said upper end and binding 80 against said barrel, a hollow apertured head removably threaded into said upper end, a removable axially bored closure for the lower part of said head, a freely reciprocable 85 rod in said body having one end extended into the bore of said closure, and a freely moving ball at each end of said rod, one supporting said rod and normally acting to close said lower aperture and the other confined within said head and normally acting 90 to close the upper end of said axial bore.

In testimony whereof, I affix my signature hereto.

CHESTER E. YOUNG.
